Primary Examiner — Mark Goodwin(74) *Attorney, Agent, or Firm* — LeClairRyan, a Professional Corporation(57) **CLAIM**

The ornamental design for a respiratory mask, as shown and described.

DESCRIPTION

FIG. 1 is a front view of a respiratory mask.

FIG. 2 is a rear view of the respiratory mask shown in FIG. 1.

FIG. 3 is a left side view of the respiratory mask shown in FIG. 1.

FIG. 4 is a right side view of the respiratory mask shown in FIG. 1.

FIG. 5 is a top view of the respiratory mask shown in FIG. 1.

FIG. 6 is a bottom view of the respiratory mask shown in FIG. 1; and,

FIG. 7 is a front perspective view of the respiratory mask shown in FIG. 1.

1 Claim, 7 Drawing Sheets---
